UNITED STATES PATENT OFFICE.

CALVIN MARSHALL, OF ST. JOSEPH, MISSOURI.

PLUMB-LEVEL.

SPECIFICATION forming part of Letters Patent No. 377,434, dated February 7, 1888.

Application filed July 5, 1887. Serial No. 243,405. (No model.)

To all whom it may concern:

Be it known that I, CALVIN MARSHALL, a citizen of the United States, residing at St. Joseph, in the county of Buchanan and State 5 of Missouri, have invented certain new and useful Improvements in Leveling Apparatus; and I do declare the following to be a full, clear, and exact description of the invention, such as will enable others skilled in the art to 10 to which it appertains to make and use the same.

My invention has relation to improvements in a combined plumb and level; and the novelty consists in the peculiar construction, combination, and arrangement of the various parts 15 for service, as will be hereinafter fully described and claimed.

The object of my invention is to provide a device of the class above named, whereby a plumb-bob may be used in combination with 20 a level in such a manner that the said plumb-bob and level will not interfere with or disturb the operation of each other, and, further, that they are adapted to be inclosed or covered and defended from wind, &c., thus rendering 25 the device true and accurate.

In the accompanying drawings, Figure 1 is a front elevation of my device. Fig. 2 is a rear elevation of the same. Fig. 3 is a vertical longitudinal sectional view, taken on the 30 line *x x* of Fig. 1; and Fig. 4 is a transverse sectional view on the line *y y*, Fig. 3.

Referring to the drawings by letter, A designates the box or casing of an ordinary level, constructed in the usual well-known manner 35 and provided at its upper end and in the front face thereof with an attaching or fastening plate, B, said plate being preferably countersunk to provide a flush or smooth surface.

C is a glass plate secured on the front face 40 of the casing, at the lower end thereof, and is also countersunk, as shown at *a*, Fig. 3.

D designates a vertical longitudinal groove or channel that is provided or formed in the middle of the box or casing, and extends from 45 the bottom of the plate B to within a short distance of the lower end of the casing, where it communicates with an egg-shaped opening, D'.

E designates a cord or wire that is suspended in the groove D by means of the plate or fastening device B, and to the lower end of this

cord or wire I attach a plumb-bob, d, which is adapted to swing in the egg-shaped opening formed in the lower end of the box or casing A, as clearly shown in Fig. 3 of the drawings. 55

It will be observed that I provide a glass plate, C', in the rear face of the box A, similar and directly opposite to the plate C, before described. It will then be understood that the egg-shaped opening D' is closed both upon its 60 front and rear faces by the said plates C C', by which construction the working of the plumb-bob is rendered visible from the outside to the eye.

F F' designate strips or blocks of the same 65 size and shape, which are adapted to fit snugly in the open front face of the groove or channel D. As will be observed by the drawings, the upper strip, F, is constructed of wood or other suitable impenetrable material, while 70 the lower strip, F', is made of glass, for the same purpose of rendering the plumb-cord visible, as the oppositely-disposed plates C C' perform the same function for the plumb-bob d.

A line may be drawn down the middle of 75 the longitudinal groove or channel D and parallel to the side edges of the box or casing A, the said line being adapted to be used in the same manner and for a similar purpose as in an ordinary plumb or spirit-level. 80

The heretofore-mentioned parts constitute the plumbing apparatus of my invention.

I will now proceed to describe the leveling device of my invention.

G is a plate, preferably of metal, that is secured by screws in any suitable manner to one side of the box or casing A, midway the length thereof, and countersunk. This plate is provided on its under surface with a perforated lug or projection, g, which extends for a slight 85 distance in a short groove or channel, H. This groove or channel communicates with an egg-shaped opening, I, corresponding to the opening D, hereinbefore described, and which also has its front and rear faces inclosed by the 90 glass plates J J'. 95

K indicates a cord or wire that is secured at its upper end to the projection or lug g, and having the plumb-bob h attached to its lower end and suspended in the egg-shaped opening I, as shown in Fig. 4.

L designates a partition or plate of glass that

is secured to one of the walls of the groove or channel H, to prevent the striking of the cord E against the cord or wire K, and also to make the crossing of the cords visible from the outside through the plates J J' of the casing.

M is a guide plate that is secured to the partition L, and perforated, as at m, to allow for the passage of the cord or wire E, as shown.

It will be seen that the two strips or blocks F F', hereinbefore described, are connected at their meeting ends to each side of the egg-shaped opening I and joined by the glass plate J.

Having described my invention, what I claim as new, and desire to secure by Letters Patent, is—

1. A spirit-level casing having channels arranged lengthwise and crosswise, as described, and a transparent division arranged at the intersection thereof and provided with a guide for one of the bob-cords, substantially as specified.

2. As an improved article of manufacture, a leveling and plumbing device comprising a case having a transverse and longitudinal groove, bobs suspended from cords in the respective grooves, and transparent face-plates for the chambers containing the bobs, substantially as specified.

3. A plumb-bob and leveling device having the case grooved and recessed, as described, the glass piece E, secured in the said recess, and the glass plates C and C' and J and J', whereby bobs placed in the case may be viewed from either side, substantially as specified.

In testimony whereof I affix my signature in presence of two witnesses.

CALVIN MARSHALL.
